UNITED STATES PATENT OFFICE.

ALBERT C. FISCHER, OF CHICAGO, ILLINOIS.

CONTAINER FORM, EXPANSION JOINTS, AND METHOD OF INSTALLING SAME.

Application filed June 19, 1922. Serial No. 569,247.

To all whom it may concern:

Be it known that I, ALBERT C. FISCHER, a citizen of the United States; residing in Chicago, county of Cook, State of Illinois, have 5 invented certain new and useful Improvements in Container Forms, Expansion Joints, and Methods of Installing Same, of which the following is a specification.

It has been the early practice in providing 10 expansion joints to place a strip of wood at the intersection in the roadway, where it is desired to provide for the expansion and contraction of the concrete, and later remove the strip and pour heated bituminous matter 15 in the crevice.

This method was superseded by pre-moulded joints installed at the time of pouring the concrete. However, it has since been found that joints with felt sides and others 20 having interfering substances on the sides do not adhere to the walls of the concrete and consequently do not keep the crevice waterproof.

It is also customary to allow the joint to 25 protrude one half to one inch above the finished surface, so that the traffic will work this edge over the edges of the concrete on either side of the joint.

When pouring the joint heretofore a V has 30 been formed by the heated material in settling, and this necessitates going over the crevice several times with heated material, until filled. But then no surplus was provided, as in the case where half to one inch 35 was allowed to project, when a premoulded joint is used.

My improvement performs two important 40 functions, it provides a means to compel adhesion to the side walls of the concrete, and also it provides a means for forming a protruding edge to take the wear of the traffic and protect the edges of the concrete. It also prevents tearing away concrete when 45 pulling the spacing board, which has been customary in removing the wooden strips.

I furnish a container form in the shape of 50 a covering which will fit the spacing board and protrude above the surface of the concrete. This envelope is made of saturated felt preferably, but may be made of any suitable substance, such as, paper, cloth, burlap, canvas or other substances. The outside is preferably coated with a fair coating of bituminous or other suitable adhesive.

The envelope is placed about the spacing or backing board and staked in position.

The concrete is poured and allowed to set. The envelope has a flanged base over which the concrete is placed and which acts as a holding means in preventing the container 60 form raising upon pulling out the backing or spacing board. When the board is removed the container remains in place and is filled with suitable filler. These fillers are usually heated to 300 or 400 degrees, and this 65 temperature will naturally compel adhesion by melting the material on the outside of the container or the material with which the container is saturated.

To better illustrate the process and parts 70 involved I refer to Figure 1 of the drawing, in which (a) represents a spacing strip of any suitable material preferably wood, and (b) a crowning strip which can be placed over the base or inserted strip (a), (b) is not necessary to the functioning of this invention except as a convenient means of holding the envelope or container in place by fitting it over the folded down ends which later will 75 be straightened and protrude, thus providing mould walls for the protruding filler.

Figure 2 indicates a container folded to receive the spacing strip (a) Figure 1. The container may be of saturated felt coated or otherwise, or of any suitable material, as 80 paper, card-board, cloth, etc.

Figure 3 illustrates the container arranged 85 so the folded ends (ff) may be straightened and become the side walls for the filler, thus forming a protruding joint after pouring. 90

Figure 4 illustrates the container folded for packing or shipping to the job (cc) representing the walls and (d-d) the folded base.

Figure 5 illustrates the container folded 95 with flaring corners or flanges (dd) so that when opened the flanges extend beneath the concrete and hold the container in place while the spacing strip (a) Figure 1 is being removed.

Figure 6 illustrates the container opened 100 preparatory to receiving the spacing strip (c-c) representing the walls and (d-d) the flanged base.

Figure 7 illustrates the container (cc) or envelope inserted with the spacing strip (a) and (b). The concrete (e) is placed on either side and formed over (d-d).

Figure 8 illustrates the concrete (e) with the spacing strip (a) removed, leaving the 110 container (cc) in place and ready to receive the heated filler.

Figure 9 illustrates the completed pavement or walk (e) representing the concrete (c), the container walls (d—d) the flanged base and (f) the protruding filler.

- 5 It may readily be understood that many modifications may be made in this invention. The joint may be installed in reservoirs, walls, sidewalks and buildings, or used for other construction purposes.
- 10 The filler may either be solid or compressible or cellular as desired. Likewise the spacing strip need not necessarily have a cap strip, and the spacing strip may be made of any suitable material that will yield to the 15 traffic in reducing the protruding part of the joint.

The container or envelope fitting over the spacing strip and later becoming the mould in the concrete, need not necessarily be restricted to straight protruding edges, but the edges may be slightly curved in, as shown in Figure 3, and may be held in place by the cap strip (b) Figure 1.

I claim:

- 25 1. The method of installing an expansion joint, which consists in placing in position at the joint to be formed a molding container together with a spacing board in said container, pouring the concrete along side 30 the partition thus provided, while the spacing board is in place, and then removing the spacing board from the container, and molding into said container a bituminous material.
- 35 2. The method of providing an expansion joint for concrete pavements, which consists in placing a partition composed of a spacing board surrounded by a mold of felt or the like carrying a material softening under the 40 influence of heat, then removing the board, and filling the mold with hot bituminous matter.
- 45 3. The method of providing an expansion joint in concrete pavements, which consists in placing a partition composed of a spacing board surrounded by a molding container, of thin flexible material, placing the concrete along side the partition thus provided, to a level below the upper margin of the con-

tainer, removing the spacing board and 50 pouring bituminous matter in the container, and building up the bituminous matter to a level above the surface of the concrete.

4. Means for forming a plastic joint for pavement sections, comprising a collapsible 55 envelope, and a mold-board fitting said envelope and sustaining it against pressure of the pavement section at the time of laying the section; said board being removable from the envelope after completion of the laying 60 operation and having a form which leaves, in the envelope, a space for receiving plastic material to complete the joint.

5. Means for forming plastic joints for pavement sections comprising an envelope 65 of collapsible material, constructed with upwardly extending sides and a laterally enlarging bottom portion, and a mold board fitting said envelope and sustaining it against pressure of the pavement section at 70 the time of laying the section; said board being removable from the envelope after completion of the laying operation and having a form which leaves, in the envelope, a 75 space for receiving plastic material to complete the joint.

6. Means for forming a water-proof plastic-pavement joint comprising a collapsible envelope of fibrous material saturated with bituminous material, and a mold-board fitting said envelope and sustaining it against pressure of the pavement section at the time of laying the section; said board being removable from the envelope after completion of the laying operation and having a 80 form which leaves, in the envelope, a space for receiving plastic material to complete the joint.

7. Means for forming an expansion joint for a sectional pavement, comprising an envelope having upwardly extending sides, a rigid mold board fitting said envelope, and a crowning strip removably fitted to the upper edge of said mold board and confining the sides of the envelope thereto.

Signed at Chicago, Illinois, this 12th day of June, A. D. 1922.

ALBERT C. FISCHER.
